UNITED STATES PATENT OFFICE.

CHARLES WM. HALE, OF EUREKA, KANSAS.

WRENCH.

SPECIFICATION forming part of Letters Patent No. 372,750, dated November 8, 1887.

Application filed May 26, 1887. Serial No. 239,502. (No model.)

To all whom it may concern:

Be it known that I, CHARLES WM. HALE, a citizen of the United States, residing at Eureka, in the county of Greenwood and State 5 of Kansas, have invented certain new and useful Improvements in Wrenches, of which the following is a specification.

My invention relates to improvements in wrenches; and it consists in certain novel features, hereinafter first fully described, and then pointed out in the claims.

In the accompanying drawings, which fully illustrate my invention, Figure 1 is a side view of a wrench embodying my improvements. 15 Fig. 2 is a similar view showing the device as it appears when being used to tighten a nut, and part of the casing being broken away. Fig. 3 is a detail view of the sliding jaw, and Fig. 4 is a detail view of the slide to which the 20 pipe-bit is secured.

Referring to the drawings by letter, A designates the handle or operating-lever, provided with an enlarged portion, a, at one end, in which a transverse groove, a', is formed.

25 B designates the forked or U-shaped shank, which is pivoted in the groove a' at the center of the same, as clearly shown. The branches b b of the shank extend from the handle a suitable distance and diverge slightly toward 30 their outer ends, which are firmly secured in the rigid jaw C by any preferred means. This rigid jaw has its opposite ends projected past the shank in the plane of the enlargement a, and its inner face at one end is made 35 plain, while at its other end it is provided with the depression or hollowed-out portion c.

D designates the sliding jaw, which moves on one of the branches b of the shank to and from the plain-faced end of the rigid jaw. 40 This sliding jaw is provided in its lower end with an opening, d, through which the branch b of the shank passes, and on its inner side, near its top, it is provided with the lugs or ears d', between which I pivotally secure the 45 end of a link or connecting-bar, E, the other end of which is pivotally secured in one end of the groove a' of the enlargement a of the handle. In the opposite end of the said groove I pivotally secure one end of the pipe- 50 bit F, the opposite end of which is inclined inwardly toward the handle and provided

with a series of teeth, f, which are adapted to bite against the pipe when the wrench is applied thereto. The outer or toothed end of the pipe-bit is supported and carried by a 55 slide, G, which is mounted on the shank in the same manner as the sliding jaw D, and is provided with two outwardly-projecting parallel lugs, g g, between which the end of the bit is adjustably secured by means of a pin or similar device inserted through the end of the bit, and one or another of a series of openings, g', formed transversely in the lugs g g. I am thus enabled to readily adjust the bit to the diameter of the pipe being operated on. 60

The operation of the device will, it is thought, be readily understood.

It will be observed that my wrench is a combined nut and pipe wrench, and as the operation of the two parts is substantially the 70 same, a description of one will suffice. When it is desired to tighten a nut, the handle is turned out, as shown in Fig. 2, forcing the sliding jaw up against the nut and clamping the same against the rigid jaw. If the handle 75 be now forced farther outward, the nut will be turned, as will be readily understood. A reverse movement of the handle will loosen the hold of the sliding jaw on the nut and allow it to slip past the corners of the same, as 80 will be readily understood, to secure a new hold on the same.

It will be seen that I have provided a simple and compact wrench which automatically adjusts itself to the nut or pipe, and it is 85 thought the advantages of the same will be readily seen without a detailed reference thereto.

Having thus described my invention, what I claim, and desire to secure by Letters Patent, is—

1. In a wrench, the combination of the handle, the shank pivotally secured thereto, the rigid jaw secured to the end of the shank, the sliding jaw moving along the shank, and the 95 link having its opposite ends pivoted, respectively, to the handle and the sliding jaw, substantially as set forth.

2. The combination of the handle, the shank pivotally secured thereto, the rigid jaw secured to the end of the shank and having a 100 depression, c, near its end, the slide moving

on the shank, and the bit having one end pivoted to the handle and its other end adjustably pivoted to the slide, substantially as specified.

3. The combination of the handle, the 5 branched shank pivoted thereto, the rigid jaw secured to the end of the shank, the sliding jaw mounted on one of the branches of the shank and connected to the handle by a piv-

oted link, the slide mounted on the other branch of the shank, and the bit pivoted to the handle and adjustably mounted in the slide, substantially as described and shown.

CHARLES WM. HALE.
